DIAMOND-TYPE DRILL BIT

Daniel A. North and James C. Posgate, Jr., Laredo, Tex., assignors, by mesne assignments, to Esso Production Research Company, Houston, Tex., a corporation of Delaware

Filed Aug. 17, 1964, Ser. No. 390,101

1 Claim. (Cl. 175—330)

This invention relates to a drill bit of the type having diamonds or similar hard cutting elements affixed thereto for the purpose of cutting or abrading away an earth formation. More particularly, the invention relates to an improved contour for diamond-type rotary drill bits.

Drill bits utilizing diamonds and similar hard materials as cutting elements enjoy peculiar advantages in drilling rock and other formations in connection with prospecting for oil wells and the like. When so utilized, the drill bits are detachably secured to the lower end of a drill pipe which is connected to a rotary drilling mechanism at the earth's surface. Rotation of the drill pipe about its axis effects rotation of the drill bit to cut and abrade the earth material against which it is forced by the weight of the drill pipe above it, and more particularly by the weight of the heavy drill collars at the lower end of the drill string. Circulating fluid such as drilling mud is pumped down through the drill string and through the bit for the purpose of flushing away the cuttings and carrying the same to the upper end of the hole, to clean the cutting faces of the bit and the diamonds embedded therein, and to cool the cutting face and the diamonds.

Diamonds may be lost from the bit as the result of failure of the matrix in which the diamonds are embedded, or as the result of shattering of the diamonds during the course of drilling operations. Shattering of the diamonds may result from vibration inherent in a long drill string, as a result of shock or impact as the bit skips or hops, or by improper dissipation of heat generated by the diamond while it's abrading away the formation. The present invention is directed to a solution of the latter cause of diamond failure.

In accordance with the teachings of the present invention, the contour of the cutting face of a diamond drill bit is such that the vertical force exerted on the drilling face during drilling operations decreases near the longitudinal axis of the drilling bit. The bit body is formed so as to have a central cutting portion and a gauge cutting portion, the central cutting portion extending inwardly and upwardly into the bit body from the lower end thereof to form a nonconverging throat, the throat terminating at a predetermined distance from the lower end of the bit so as to have a radius r_o thereat, the cross-sectional profile of the cutting portion being formed substantially according to the equation

$$y = r_o + \frac{1}{K_o} (\cos^{-1} e^{-K_o L} - \cos^{-1} e^{K_o (x-L)})$$

where $e^{-K_o L}$ is a constant having a value between .65 and 0.1, and preferably between .112 and .0205, x being measured along the longitudinal axis of the bit from the upper end toward the lower end of the central cutting portion, y being measured from the longitudinal axis of the bit, and L being the length of the throat from

2

the upper end to the lower end of the central cutting portion.

Objects and features of the invention not apparent from the above discussion will become evident upon consideration of the following detailed description of the invention taken in connection with the accompanying drawing, wherein:

FIGS. 1 and 2 are cross-sectional views of prior art types of drilling bits herein shown for the purpose of illustrating the defects in the prior art;

FIG. 3 is a cross-sectional view of a drilling bit formed in accordance with the present invention; and

FIG. 4 is a rectangular coordinate graph useful in design calculations according to the invention.

With reference now to FIG. 1, there is shown a drilling bit having a stock 1 to which is affixed a matrix 3 in which are embedded a plurality of diamond-type cutting elements 7. The lower end of the bit may be described as being semi-toroidal in cross section such that a cross section of the lower end of the cutting face of one-half of the bit is substantially semi-circular. The prior art bit illustrated in FIG. 2 having a stock 9, a matrix 11, and drilling elements 13 has a different drilling face contour such that the lower end 14 is shifted nearer the longitudinal axis of the bit. Each type of bit is usually provided with a multiplicity of water courses 5 for the purpose of allowing circulation of drilling fluid across the lower end of the bit. As the bits are rotated, a core is formed which may pass up through the center 30 of the bit if the bit is used in coring type operations, or may be broken and passed through a side port if the bit is used in extended drilling operations. The means for disposing of the central core is not a part of this invention and is not described herein. Various types of 35 means for disposing of cores are well known to the art. A particularly effective type is that illustrated and described in U.S. Patent 2,931,630, Grady.

The areas of the prior art type of drilling bits whereat failure of the diamond elements is most prevalent are indicated beneath the bits and designated by reference numerals 10 and 15. It will be noted that these critical wear areas are near the longitudinal axis of the bit. In these areas the heat dissipating capacity of the bit decreases whereas the cutting requirements remain quite high. The formation removed under any diamond is proportional to the cutting ability of the diamond, which is a function of the vertical component of the unit bearing load applied to that diamond, and of the linear tangential velocity, which latter quantity is a function dependent upon the distance of the diamond from the longitudinal axis of the bit. Manifestly, it is desirable to have the incidence of failure of the diamond equalized over the drilling face if the bit is to drill the greatest amount of hole during its drilling life.

With reference now to FIG. 3, there is shown a drill bit formed in accordance with the present invention. The stock of the bit is designated by the reference numeral 17, the matrix by the reference numeral 19, and some of the diamond-type drilling elements by the reference numeral 21. The upper end of the stock of the bit is illustrated as having internal threads 23 as is customary when the bit is to be affixed to a core barrel. However, a threaded pin may be utilized, such as illustrated in the Grady patent, supra. Furthermore, if the bit is to be used for the purpose of extended drilling oper-

ations rather than for the purpose of drilling a core, there must be incorporated core-breaking apparatus such as illustrated in the Grady patent, *supra*, or other types of core breakers known to the art. Such core-breaking apparatus is not illustrated inasmuch as it forms no part of the present invention. It is assumed that drilling fluid will circulate either down through the center of the bit through flow channels and up the annulus between the drill pipe and the sides of the borehole, or in the reverse direction, depending upon the drilling technique to be used. Fluid jet-forming ports also may be utilized such as are illustrated in the Grady patent, *supra*.

It will be recognized that the profile of the drill bit is substantially the reverse of that utilized in diamond-type bits used heretofore, such as that illustrated in FIG. 2. The drilling face comprises a central cutting portion 27 extending from the lower end 29 of the bit inwardly and upwardly into the bit body and terminating at a distance L from the lower end 29 at a plane designated by the reference numeral 31 whereat the drilling face has a radius r_o . In effect, the drilling face forms a throat of length L, of minimum radius r_o , and of maximum radius R, which later radius may be designated the working radius of the drilling face. The drilling face also comprises a gauge cutting portion 33 extending upwardly and outwardly from the lower end 29 of the bit, which may be of any convenient form, for the purpose of cutting the hole to gauge. Diamond failure over the gauge cutting portion has not been found to be a problem, and the contour of the gauge cutting portion is not critical to the present invention.

As indicated above, the cross-sectional cutting surface

fined as the ratio of the throat length L to the working bit radius R. The factor K_o can be evaluated by a trial and error calculation where values of K_o which make the product $K_o R$ equal to or less than 1.57 radians are substituted into the formula $\cos K_o R = e^{-K_o L}$ until it becomes an equality. In FIG. 4 there is shown a graph of the quantity $e^{-K_o L} = C$ as the function of the shape factor for use in evaluating K_o without resorting to trial and error calculations.

The technique of determining the shape of the central cutting portion of a bit in accordance with the present invention will be best understood from the following example. Let it be assumed that the bit outside diameter is 4 1/4 inches, that the pencil core size (i.e., 2 r_o) is to be 1 inch in diameter, and that the shape factor is to be 2.00. Considering a 1/4-inch fillet radius on the bit outside diameter, the drilling diameter would be 4.25 inches. The working radius is equal to one-half the drilling diameter of the central cutting portion minus r_o , which will give a value of 1.625 inches. Therefore, considering the shape factor of two, the throat length will be two times the working radius, or 3.25 inches. The term $e^{-K_o L}$ can be found from the formula

$$25 \quad K_o = \frac{1n c}{L}$$

to be equal to .9375 in.⁻¹. The formula for the profile of the central cutting portion will be

$$30 \quad Y = .5 + \frac{1}{.9375} [\cos^{-1} e^{-0.9375(3.25)} - \cos^{-1} e^{0.9375(x-3.25)}]$$

Substituting various values of x between 0 and 3.25 in this formula will give the following table:

X In.	$K_o(x-L)$	$e^{K_o(x-L)}$	θ_2 Deg.	θ_2 Rad.	θ_1 Rad.	$\theta_1 - \theta_2$ Rad.	$\theta_1 - \theta_2 / K_o$	$\theta_1 - \theta_2 / K_o + r_o = Y$
0	3.051	0.0475	87.3	1.53	1.53	0	0	0.500
1.0	2.110	0.1212	83.2	1.45	-----	0.08	0.085	0.585
1.5	1.641	0.1939	78.8	1.376	-----	0.154	0.164	0.664
2.0	1.170	0.3104	71.9	1.25	-----	0.28	0.299	0.799
2.25	0.9375	0.3914	67.0	1.17	-----	0.36	0.384	0.884
2.50	0.7031	0.4944	60.4	1.05	-----	0.48	0.512	1.012
2.75	0.469	0.6240	51.4	0.897	-----	0.63	0.672	1.172
3.00	0.234	0.780	38.7	0.674	-----	0.86	0.917	1.417
3.25	0	1.00	0	0	-----	1.53	1.63	2.13

profile of the central cutting portion 27 of the bit is formed in accordance with the equation

$$y = r_o + \frac{1}{K_o} (\cos^{-1} e^{-K_o L} - \cos^{-1} e^{K_o(x-L)})$$

where

r_o is the radius of the core

$e^{-K_o L}$ is a constant having a value between .65 and .01, and usually has a value between .112 and .0205

x is measured along the longitudinal axis of the bit from the upper end toward the lower end of the central cutting portion

y is measured from the longitudinal axis of the bit.

The constant K_o is determined from the equation

$$\cos K_o R = e^{-K_o L}$$

$$K_o R = 1.57 \text{ radians}$$

Manifestly, the working radius R ranges between the limitation of 0 and 1.57 radians if K_o is set equal to unity, while L may increase without limit. As L is increased, the throat length of the bit becomes greater and the ratio L/R becomes greater. In order to obtain a working solution, some parameter must be introduced whereby the working radius becomes the independent variable. The diameter of the hole to be drilled, and therefore the radius of the bit, will always be known. The parameter relating the working radius R and the throat length L to K_o may be termed the "shape factor," which can be de-

A coordinate plot of this table will yield the desired bit profile.

It is readily apparent that the bit profile resulting from the present invention will produce a lower bearing pressure and will cause less abrading work to be done per diamond so that there is less heat to be dissipated by the diamond. However, this fact is compensated for by the fact that there is a substantial increase in the number of diamonds as one progresses inwardly toward the longitudinal axis of the bit. The cutting rate of the drilling face is substantially equalized across a plane normal to the longitudinal axis of the bit. The rate of heat generation is matched to the dissipating capacity of the bit in each area of the central cutting portion of the bit. Therefore, the probability of failure of the cutting elements is substantially equalized throughout the central cutting portion of the bit.

Although the embodiment disclosed in the preceding specification is preferred, other modifications will be apparent to those skilled in the art which do not depart from the scope of the broadest aspects of the invention.

What is claimed is:

A drill bit comprising a bit body having a central cutting portion and a gauge cutting portion, said central cutting portion extending inwardly and upwardly into said bit body from the lower end thereof to form a non-converging throat, and terminating therein at a predetermined distance from said lower end, said throat having a radius r_o at said predetermined distance from said lower

end, the cross-sectional profile of said central cutting portion being formed substantially according to the equation

$$y = r_o + \frac{1}{K_o} (\cos^{-1} e^{-K_o L} - \cos^{-1} e^{K_o (x-L)})$$

where

r_o is the radius of the core

$e^{-K_o L}$ is a constant having a value between .65 and .01

x is measured along the longitudinal axis of the bit from

10

the upper end toward the lower end of the central cutting portion

y is measured from the longitudinal axis of the bit.
